RICHARD D. KEHOE, OF NEW YORK, N. Y.

PULP SHREDDING APPARATUS

Application filed December 6, 1928. Serial No. 324,247.

This invention is directed generally to a method of and means for shredding paper pulp, in order to prepare the pulp for further treatment, for instance drying, as may be necessary for its convenient transportation and storage until required for use.

Pulp of this character in its final delivery from the pulp machine is in sheet form from which a considerable portion of the moisture content has been driven off by expressing rollers between which the pulp is forced during the sheet formation. Incidentally, owing to the manner in which the pulp mass is initially collected on the suction roll, the pulp is in substantially layer form, so that when finally delivered from between the expressing rollers, the pulp is in the form of a sheet made up of a series of layers which form a compact body, but in which the layer formation is clearly evident in any attempt to separate the pulp.

The pulp, following its delivery from the pulp making machine, still contains a considerable proportion of moisture content, and if shipped in this form is extremely liable to deterioration, to say nothing of the added shipment weight due to the moisture, and the liability of the pulp freezing in cold weather as a result of its moisture content. These well known disadvantages tend to a considerable loss and increased expense in the use of the pulp for the making of paper.

In an endeavor to overcome these disadvantages, it has been heretofore proposed to subject the pulp, following its delivery from the pulp making machine, to certain treatment, in order that the pulp may be prepared for shipment and storage in a manner which will avoid deterioration of the pulp or any appreciable loss incident to shipment and storage prior to the use of the pulp in the making of paper. These treatments, among other things, involve the step of drying the pulp to expel the moisture content thereof in order that the pulp may be shipped

in as light a condition as possible and prevented from any deterioration incident to otherwise present moisture. The compact mass condition in which the pulp is delivered from the pulp machine renders it practically impossible to handle the pulp for drying treatment in this condition, and therefore the effective treatment of the pulp requires that it be shredded as far as possible into flocculent form and at the same time broken up into relatively small masses or particles in order that it may be effectively dried in a comparatively short space of time and with the minimum use of heat.

A very material and important factor enters into the pre-treatment of the pulp and that is the necessity for maintaining the integrity of the fibers of the pulp to the maximum extent possible during treatment. The strength and character of the paper made from the pulp depends not only upon the inherent character of the pulp proper but upon the strength of the fibers of the pulp, it being quite apparent that the longer and stronger the fibers the better the grade of paper with respect to strength. It is, therefore, of the utmost importance that in any method or means employed for the breaking up or so-called shredding of the pulp as a preliminary step to the drying treatment thereof, due regard must be had for the maintenance of the original fiber length and relation insofar as possible, for if the fibers are cut or broken, the value of the particular pulp for use in paper making is materially reduced.

The primary object of the present invention, therefore, is the provision of a method for initially treating or shredding the pulp in a manner to separate the layers into flocculent form and break up or divide the pulp mass or layers into relatively small pieces or particles to insure effective after-drying, the method being particularly designed to carry out the result stated without injury to the

views illustrating the operation of two successive rows of shredder teeth.

Figure 9 is an edge view of the pulp body illustrating the shredding result of the shredder teeth on the part acted on.

Figure 10 is a plan illustrating more or less diagrammatically the result of the shredder teeth on the pulp mass.

The pulp, indicated at 1, is delivered between pressure rolls 2 and 3, passing outwardly therefrom on a line substantially tangential to the rolls in the form of a compact sheet of appropriate width and appreciable thickness. In the making up of the pulp, as the well understood result of a pulp machine, the pulp is initially deposited on the suction rolls in substantially layer form, so that while the pulp is delivered between the pressure rolls in the form of a sheet, this sheet is in effect made up of well defined layers which, while possibly of irregular width and length with respect to the sheet, are nevertheless true layers.

Mounted for rotation adjacent the pressure rolls 2 and 3 of the pulp sheet is what may be termed the shredding cylinder 4. This cylinder, which may be driven in any appropriate manner as for example by a belt 5, is arranged to rotate at a speed materially in excess of, in fact many times the speed of, the pressure pulp rolls 2 and 3, so that in operation the shredding implement carried by the cylinder 4 intercept and pass into and through the body of the pulp projected beyond the pressure rolls.

The peripheral surface of the shredding cylinder is provided with a plurality of shredding implements or teeth 6 which are of peculiar formation, as illustrated more particularly in Figure 3. These teeth, which are of identical formation, include shanks 7 by which the teeth may be secured in the peripheral surface of the cylinder 4, and a body 8 which projects beyond the surface of the cylinder. This body in side elevation curves from the plane of the cylinder forwardly and downwardly in the direction of cylinder movement and is of substantially oval form in cross section.

The teeth from its juncture with the cylinder gradually tapers in all dimensions towards its free end, which free end is substantially a point 9 for effective entrance of the tooth into the pulp mass. It is to be particularly noted that the edges of the tooth, that is the extremities of the major diameter of the oval formation, are not sharp or of cutting form but are rather rounded or more effectively blunt to avoid any direct cutting action. The teeth are peculiarly arranged with respect to the surface of the cylinder. Thus, the surface of the cylinder may be formed of cross bars 10 having longitudinally ranging slots 11 in which the teeth, or more particularly the shanks 7 thereof, are adjust-

ably held by nuts on the ends of the shanks inwardly of the bars.

The teeth are thus disposed in rows longitudinally of the peripheral surface of the cylinder, and are designed to be arranged in more or less close proximity one to the other. The teeth of one row are out of circumferential alignment with the teeth of the next preceding row, that is, the teeth of each row are offset circumferentially and preferably disposed in a plane passing between adjacent teeth of the next preceding row. By this means, that is the close relation of the teeth of each row and the offset relation of teeth of succeeding rows, any two rows of teeth are practically effective for cooperating with the full width of the pulp mass.

With particular reference to Figures 5 to 8 inclusive, the operation of the shredder will be clearly apparent. Bearing in mind that as described, the pulp mass 1 is advancing into the path of the shredding teeth and that the latter are traveling in a circular path which intercepts the path of the advancing pulp mass, with such teeth moving at a speed many times greater than the similar movement of the pulp mass, it will be apparent that the row of teeth 6, first encountering the free end of the advancing pulp mass, will enter said mass by means of the teeth points 9 throughout the full width of the mass and at slightly spaced points thereof. Under the movement of the shredding cylinder, the initial set of teeth tend to slightly depress the pulp mass as they enter the latter, the parts assuming the position more clearly indicated in Figure 6.

The relative movement of the shredding teeth in the pulp mass continues, the teeth moving through the pulp and forming what may be termed incisions or narrow channels in the pulp mass which, as the teeth leave, tend to draw out the pulp in advance of the teeth, so that as the teeth leave the pulp, the latter is drawn out from its hard compact condition into a more or less fluffy, flocculent form throughout the area which has been reached by the teeth. As the next succeeding row of teeth reach the pulp mass, it being understood that meanwhile the pulp mass has slightly advanced, such second row of teeth will repeat the operation of the first row, forcing themselves into the pulp mass slightly in rear of the line of entry of the first teeth, and moving through the pulp mass, into and out of the same, pulling out in effect the pulp material in advance of the teeth as they move through the mass. As stated, the teeth have no cutting action and hence their entry into, passage through, and separation from the pulp mass tend to rake out or pull the pulp material in advance of the tooth, so that said material is pulled out into a light, fluffy mass without necessarily separating this mass from the pulp body.

The pulp mass is, as stated, in layer form, and these layers constitute a natural line of cleavage when their inherent adhesion incident to the compactness of the pulp body is overcome. Therefore, as the teeth operate to successively pull out portions of the pulp body into a fluffy, flocculent form, it will be apparent that this pulling out tends to destroy the adhesive relation between the layers, with the result that at irregular points the action of the teeth will tend to so destroy the adhesive relation between the layers by the fluffing up of the pulp mass that small, irregular portions of the pulp mass are separated from the body and delivered into those irregular, fluffy, flocculent particles or small masses which it is the aim of the present invention to produce. Of course, the action of the teeth proper will to some extent tend to separate the pulp mass into irregular masses incident to the pulling out operation, but primarily the teeth function to separate the pulp mass into a light, flocculent and fluffy condition, and the separation of the pulp mass into the small particles is incident to the layer separation of the pulp mass following the breaking down of the adhesive capacity between the respective layers.

The operation of the shredder of course is searchingly effective on the full mass of the pulp as the latter is directed by the pressure rolls. The action of the shredding teeth is more in the nature of a raking effect to separate the pulp mass from its compact condition into a light, fluffy, flocculent condition and the breaking up of this mass into irregular particles, each and all of which are light, flocculent and open. By the entire absence of any cutting action, it will be apparent that the breaking up of the pulp mass by the teeth does not tend in any way to a breaking down or dividing of the natural fibers of the pulp. These fibers in their relative lengths and positions remain substantially intact in each separated mass incident to the use of the shredders and thus this most important characteristic of the pulp, namely the length and integrity of its fibers, is not disturbed, and hence the value of the pulp for subsequent paper making is equally as good following the shredding operation as it was before the shredding operation took place.

The irregular, fluffy, and flocculent particles resultant from the action of the shredders is, if desired, delivered into a chute, indicated at 12, from which the masses may be delivered for further treatment. If, as contemplated, such further treatment consists in the drying of the pulp to remove the moisture content therefrom, it is apparent that the treatment of the pulp in such drying operation is materially shortened in point of time and effectively perfected with less heat where the pulp is in the shape of comparatively small, light, fluffy, flocculent particles than

if the pulp were in the hard, compact mass delivered from the pressure rolls. With the light, fluffy particles, a comparatively short heat treatment with a comparatively moderate heat degree will result in abstracting the moisture content, for the pulp mass is open, its fiber parts well separated, and the heat can do its work rapidly and effectively.

The characteristic feature of the present invention is the shredding of the pulp into light, fluffy, irregular masses without breaking down or dividing the natural fibers of the pulp mass, with the shredding action avoiding any cutting of the pulp mass, and with such shredding action operating in a manner to take full advantage of the layer formation of the pulp mass in order to facilitate the separation of such mass into the desired small, flocculent particles.

It is to be understood that the method is distinguished from that method of shredding wherein mere tearing the pulp into small pieces, or finely dividing the pulp as by a rake or carding is concerned. Putting it another way, the various layers of each piece or section of the pulp torn from the mass is made fluffy or flocculent to release and open up the fibers for quick and ready subsequent treatment.

What is claimed to be new is:

1. A method of shredding pulp, consisting in delivering the pulp in sheet form to the shredder to provide an unsupported area to receive the action of the shredder, operating the shredder at a speed in excess of the movement of the pulp to act on the unsupported portion of the sheet pulp to initially deflect said unsupported portion in the direction of shredder movement to thereby cause the plane of the pulp layers to approach the plane of operation of the shredder, with the result of pulling the outer layer into fluffy form and then breaking up the layers without breaking down or injuring the fibers of the pulp.

2. A method of shredding pulp, consisting in advancing the pulp in sheet form to the shredder to provide an unsupported area to receive the action of the shredder, operating the shredder in a path intersecting the path of movement of the pulp and at a speed materially in excess of pulp movement to act on the unsupported portion of the sheet pulp to initially deflect said unsupported portion in the direction of shredder movement to thereby cause the plane of the pulp layers to approach the plane of operation of the shredder, with the result of causing the shredder implements to leave the pulp with a relative pulling action, to produce a flocculent condition of the pulp throughout the area affected by the shredder.

3. A method of shredding pulp, consisting in operating a series of shredding implements in a circular path, feeding the pulp mass as

an unsupported area in a path intersecting the path of movement of the shredding implements, maintaining different relative speeds of the shredding implements and 5 pulp, and permitting limited bodily movement of the unsupported area of pulp mass in the direction of travel of the shredder during the shredding operation.

4. A pulp shredding apparatus including 10 means for delivering pulp in sheet form to the shredder to provide an unsupported pulp section adjacent the shredder, and a shredder operating at a speed in excess of the travel of the pulp and comprising a plurality of teeth 15 which are moved into and out of the pulp to bodily deflect the unsupported section of the pulp in the direction of movement of the teeth and pull the surface layers out in fluffy form and at the same time break up the pulp 20 sheet into comparatively small masses.

5. A pulp shredding apparatus comprising a roll over which the pulp is delivered in sheet form and beyond which the pulp is otherwise unsupported, a cylinder body revolving 25 adjacent the roll and at a speed in excess of that of the roll, and a plurality of non-cutting shredding teeth carried by the surface of the cylinder, the teeth moving in a path to intercept the path of the unsupported portion of 30 pulp beyond the roll.

6. In a shredding apparatus, a shredding cylinder provided with non-cutting shredding teeth arranged on its periphery, the teeth being disposed in rows axially of the cylinder 35 with the teeth of each row offset with respect to the teeth of the preceding row in the direction of movement of the cylinder, said teeth projecting beyond the surface of the cylinder on an outwardly and downwardly curved 40 line.

7. In a shredding apparatus, a shredding cylinder having shredding teeth thereon, each tooth being of substantially oval form in cross 45 section and forwardly and downwardly curved with respect to the surface of the cylinder, each tooth being of gradually reduced dimensions toward its free end and having a substantially pointed terminal.

8. A method of shredding pulp, consisting 50 in feeding the pulp in sheet form to the shredder to provide an unsupported section of pulp to receive the action of the shredder operating the shredder at a speed in excess of the feeding movement of the pulp and in a plane crossing the feeding line of the pulp, and causing the shredder to initially deflect the unsupported section of the pulp toward the operating plane of the shredder and thereafter separate portions of the deflected pulp from the body thereof incident to the relatively increased speed of the shredder.

9. A method of shredding pulp, consisting 55 in feeding the pulp in sheet form toward the shredder to provide an unsupported section of pulp to receive the action of the shredder,

operating the shredder in a circular plane crossing the feeding line of the pulp and at a speed in excess of the feeding movement of the pulp, and completing the shredding of the pulp incident to the deflection of the 70 unsupported section of the pulp from its feeding line toward the operating plane of the shredder and the movement of the shredder into the deflected pulp incident to the relatively increased speed of movement of the 75 shredder.

In testimony whereof I affix my signature.
RICHARD D. KEHOE.

UNITED STATES PATENT OFFICE

ERNST KORTEN, OF FRANKFORT-ON-THE-MAIN-FECHENHEIM, GERMANY

PROCESS FOR PRODUCING AMINO DERIVATIVES OF HEXAHYDRODIPHENYL

No Drawing. Application filed June 14, 1930, Serial No. 461,257, and in Germany March 2, 1928.

This application is a continuation in part of my application Serial No. 343,570, filed February 28, 1929.

I have found, that the three-nuclear condensation products which correspond probably to the general formula:

10

15

ished when the amount corresponding to one molecular proportion is taken up. By fractional distillation in vacuo a colorless oil boiling at 168-170° under a pressure of 13 mm. is obtained after small amounts of lower boiling fractions have passed over. The new 4-amino-3-methyl-1'.-2'.3'.4'.5'.6'.-hexahydro-1.1'-diphenyl thus produced in a nearly theoretical yield corresponds probably to the formula:

55

60

65

It represents when pure a transparent oil boiling at 175-177° under a pressure of 15 mm., solidifying below 0°.

The process may be carried out likewise when using a catalyst containing about 20% nickel, reduced at about 500° and precipitated on fuller's earth or silica-gel and heating the mixture under a hydrogen pressure of 10 atmospheres.

Example 2

75

In an open vessel provided with a stirrer and inlet and delivery tubes for gas a solution of 50 parts of 4.4'-diamino-diphenyl-cyclohexane in about 100 parts of tetrahydronaphthalene is heated with addition of 3 parts of a catalyst under ordinary pressure at 130-180° while introducing a current of hydrogen, which advantageously circulates. A suitable catalyst is obtained for instance by precipitating a solution containing about 85% nickel, 15% copper and 5% cerium with sodium carbonate for about 5-10% of its weight.

The course of the reaction can be easily controlled by the fact that in a sample taken out from time to time, when dilute sulphuric acid is added, an increasing amount of the sulphate of the formed 4-amino-hexahydrodiphenyl is precipitated. The warm reaction mass is separated from the catalyst and the solvent is expelled from the solution by steam. The hydrochloric acid is added to the residue, from which on cooling the hydrochloric salt of 4-amino-hexahydrodiphenyl crystallizes.

100

20 The hydroaromatic residue may be substituted by an alkyl- or alkoxygroup, are converted in one operation into aminoderivatives of hexahydrodiphenyl by treating the three-nuclear products immediately with hydrogen in the presence of a base metal hydrogenation catalyst, advantageously under superatmospheric pressure and with addition of a suitable diluent.

25 The aminoderivatives thus obtained are identical with those formed according to the process described in the parent application.

30 In order to further illustrate my invention the following examples are given, the parts being by weight and all temperatures in centigrade degrees; but I wish it to be understood that my invention is not limited to the examples given, nor to the exact conditions stated therein:—

Example 1

35 50 parts of 4.4'-diamino-3.3'-dimethyl-diphenyl-cyclohexane, 50 parts of decahydronaphthalene and 2.5 parts of a catalyst, prepared by precipitating the carbonates of nickel, cobalt, copper and bismuth on silica-gel and reducing in a hydrogen atmosphere in the usual manner, are heated to 180° while well stirring under a hydrogen pressure of 60 atmospheres. The absorption of hydrogen 40 occurs rather quickly. The reaction is fin-
